US0D1079732S

(12) **United States Design Patent** (10) **Patent No.:** **US D1,079,732 S**
(45) **Date of Patent:** **** Jun. 17, 2025**

(54) **DISPLAY SCREEN OR PORTION THEREOF WITH A GRAPHICAL USER INTERFACE**

(71) Applicant: **HUAWEI TECHNOLOGIES CO., LTD.**, Guangdong (CN)

(72) Inventors: **Lina Tao**, Shenzhen (CN); **Anqi Liu**, Shenzhen (CN); **Fei Ye**, Wuhan (CN); **Yufeng Huang**, Shanghai (CN)

(73) Assignee: **HUAWEI TECHNOLOGIES CO., LTD.**, Shenzhen (CN)

(**) Term: **15 Years**

(21) Appl. No.: **29/813,174**

(22) Filed: **Oct. 27, 2021**

(30) **Foreign Application Priority Data**

Apr. 29, 2021 (CN) 202130254352.0

(51) **LOC (15) Cl.** **14-04**

(52) **U.S. Cl.**

USPC **D14/486**

Primary Examiner — Jack Reickel

(57) **CLAIM**

The ornamental design for a display screen or portion thereof with a graphical user interface, as shown and described.

DESCRIPTION

FIG. 1 is a front view of a first embodiment of a display screen or portion thereof with a graphical user interface showing our new design;

FIG. 2 is a front view of a second embodiment of a display screen or portion thereof with a graphical user interface showing our new design; and,

FIG. 3 is a front view of a third embodiment of a display screen or portion thereof with a graphical user interface showing our new design.

The dash-dot broken lines in the drawings illustrate the display screen or portion thereof and form no part of the claimed design.

1 Claim, 3 Drawing Sheets
